PAD-A-MONTH DESK CALENDAR

John P. Wege, St. Paul, Minn., assignor to Brown
& Bigelow, St. Paul, Minn., a corporation of
Minnesota

Application April 15, 1937, Serial No. 137,014

5 Claims. (Cl. 281—19)

My invention relates to an improvement in desk calendars of a type designed to provide a personal record and a daily appointment list or record, as well as providing information as to the date.

5 It is the object of my invention to provide a desk pad which is positioned in a way to ordinarily conceal the personal record and memorandum, while at the same time exposing the list of daily appointments or daily records which have been kept. In this way, confidential information may be ordinarily concealed in such a way that it will be readily accessible for use. This object is accomplished by providing a pad 10 having a cover which overlaps only a portion of the pad. The remaining portion of the pad bearing a list of appointments or notations for the different days of the week is open and in constant view.

10 It is a feature of my invention to provide a desk pad construction in which a cover partially overlaps the desk pad and to weight this cover to a considerable extent so as to hold the pages beneath the cover constantly flat. The cover in this way acts as a paper weight to keep the portion of the pad beneath the same neat and in proper shape. It also acts to prevent wind from opening up the cover of the pad at an inopportune time, thereby concealing confidential information.

15 30 on the personal record beneath the weight. The weighted cover also serves to ascertain that the cover lies flat either in the position overlying the personal record portion of the pad, or else in open position. Accordingly the pad is simple and easy to use as the cover holds one end of the sheets in place if writing is done upon the daily memorandum portion of the sheets, and as the cover is entirely out of the way if writing is done on the personal record portion of the sheets.

35 40 It is the idea of the present invention to provide a calendar having an interchangeable pad secured therein which may be removed at the end of a month and the personal record thereof retained as a permanent memorandum. The pad is replaced each month with a new pad, providing a record for the days of the new month.

These and other objects and novel features of my invention will be more clearly and fully set forth in the following specification and claims.

50 In the drawing forming a part of my specification:

Figure 1 is a perspective view of my pad in closed position.

Figure 2 is a top plan view of my pad in open position.

Figure 3 is a cross-sectional view taken on the line 3—3 of Figure 2.

Figure 4 is a cross-sectional view taken on the line 4—4 of Figure 2.

My pad A comprises a base 10 and a cover 11 connected together along a flexible portion 12. When in folded position illustrated in Figure 1, the cover 11 partially overlaps the base 10 and a pad 13 secured thereto.

The base 10 is formed of a stiffening sheet 14 10 having a pocket forming sheet 15 overlapping the same. A binding tape 16 is adhered over the outer edge 17 and top and bottom edges 19 of the base 10, securing the pocket forming sheet 15 marginally to the stiffening sheet 14. A base 15 sheet 20 extends over the bottom surface of the stiffening sheet 10 and overlaps the binding tape 16, thus sealing the lower surface of the stiffening sheet 14. The extreme end 21 of the covering sheet 22 of the cover 11 extends in overlapping 20 relationship with the stiffening sheet 14 and the base sheet 20 overlaps this end 21.

A strip 23 of flexible covering material extends over the stiffening sheet 14 sufficiently to extend beneath the free end of the pocket forming sheet 15. The upper surface of the stiffening sheet 14 is in this way concealed from view by a portion of the flexible strip 23 and by the pocket forming sheet 15. A pocket covering sheet 24 is adhered to the upper surface of the pocket forming sheet 15 and overlies the binding tape 16 to provide a continuously sealed joint between the covering sheet 24 and the tape 16.

The cover 11 is formed with a soft padding sheet 25 provided within the covering sheet 22, 35 to cushion the cover 22 from a metal plate 26 which acts as a stiffening member for the cover and as a weight therefor. The end 27 as well as the edges 29 thereof, fold over the plate 26 and are adhered thereto. The end 30 of the flexible strip 23 overlaps one edge of the plate 26 and is adhered thereto. A securing sheet 31 overlies the inturned edges 27 and 29 and the edge 30 of the strip 23, and more securely holds these edges to the plate 26.

45 Overlying the sheet 31, I provide a pocket formed as best illustrated in Figure 4 of the drawing. The pocket is formed with a stiffening sheet 32 extending virtually the entire area of the inner surface of the cover 11 and having a 50 backing sheet cover 33 extending over the same, and having an edge 34 folded over the edge of the stiffening sheet 32. The pocket is formed with a stiffening sheet 35 having a pocket covering sheet 36 extending over the same and ad- 55

hered thereto. The covering sheet 36 is provided with one edge 37 extending over the free edge of the stiffening sheet 35 to form a folded edge adjacent the pocket. The other edges 39 of the sheet 36 are folded over the backing or stiffening sheet 32 and edges 34 of the cover 33 therefor. The edges 39 of the pocket, and the edges 34 of the covering 33 not covered by the edges 39 are adhered to the sheet 31. The pocket 10 is in this way secured to the cover 11. A calendar sheet 40 which is removable and replaceable is inserted in the pocket.

In the pocket formed by the sheets 15 and 24 of the base portion 10, I extend the anchoring tongue 41 of a pad 13. The tongue 41 is bound by a binding tape 42 into a book form with a pad of sheets 43 and a blotter 44. The blotter 44 is provided with a row of perforations 45 along which this blotter may be removed for use upon the desk. The sheets of the pad 43 are provided with a personal record portion 46 which is connected along a perforated line 47 with a daily memorandum portion 49. The personal record portion 46 is concealed by the cover 11 when the cover is in closed position illustrated in Figure 1, while the daily record portion 49 is constantly visible.

The weight of the metal plate 26 holds the cover portion 11 either in folded or unfolded position. The personal record portion and the calendar 40 are concealed when the cover 11 is closed.

In accordance with the patent statutes, I have described the principles of construction of my desk pad and calendar, and while I have endeavored to set forth the best embodiment thereof, I desire to have it understood that this is only illustrative of a means of carrying out my invention and that obvious changes may be made within the scope of the following claims without departing from the spirit of my invention.

I claim:

1. A desk pad comprising a base, a pad mounted thereupon, and a weighted cover secured to said base, said cover including a heavy metal filler, said cover being of proper dimensions to cover a portion of said pad, leaving the major portion thereof exposed.

2. A desk pad comprising a base, a paper pad mounted thereon, said paper pad comprised of sheets bound along one edge, said sheets being divided by a perforated line parallel the bound edge, a cover including a heavy metal filler hingedly secured to said base parallel and adjacent the bound edge of said pad, said cover covering said pad on one side of said perforated line but leaving the remaining portion thereof exposed.

3. A desk pad comprising a base, a pocket therein, a pad of sheets bound along one edge, a tab bound with said sheets engageable in said pocket, a cover hingedly secured to said base, a heavy metal plate embedded in said cover, said cover covering a portion of said pad and leaving a substantial portion thereof exposed.

4. A desk pad comprising a base, a pocket 25 therein, a pad engageable in said pocket, sheets in said pad divided into two parts separated along a dotted line, a cover including a filler of heavy material to act as a paper weight on said base, said cover extending over and concealing in 30 closed position one of said parts, and exposing the other of said parts.

5. A desk pad comprising a base including a rectangular stiffening sheet, a pocket forming sheet bound along three edges to said stiffening sheet, a cover comprising a heavy metal weight plate, a cover sheet for said plate, means securing said cover sheet to said stiffening sheet of said base, and a pocket on said cover.

JOHN P. WEGE. 40
